US0D1063869S

(12) **United States Design Patent** (10) **Patent No.:** **US D1,063,869 S**
(45) **Date of Patent:** **** Feb. 25, 2025**

(54) **REMOTE CONTROL**

(71) Applicant: **Crestron Electronics, Inc.**, Rockleigh, NJ (US)

(72) Inventors: **Daniel Previti**, Tappan, NY (US); **Gautham Basti**, Bengaluru (IN); **Howard Balch**, Bloomingdale, NJ (US); **Chetan Khanna**, New City, NY (US)

(73) Assignee: **Crestron Electronics, Inc.**, Rockleigh, NJ (US)

(**) Term: **15 Years**

(21) Appl. No.: **29/887,670**

(22) Filed: **Mar. 23, 2023**

(51) LOC (15) Cl. **14-03**

(52) U.S. Cl.

USPC **D13/168**

(58) **Field of Classification Search**

USPC D13/123, 133, 152, 154, 156, 158, 160, D13/162, 1, 163, 164, 168, 169, 170, 171, D13/173, 174, 177, 178, 184, 199; D14/188, 218, 358, 385, 456, 496

CPC H02J 13/00022; H04L 2012/2841; H04L 67/025; H04L 2001/0097; H04M 11/007; H04M 1/72415; A47C 31/008; A61G 2203/12

(57) **CLAIM**

The ornamental design for a remote control, as shown and described.

DESCRIPTION

FIG. 1 is a front perspective view of a remote control;

FIG. 2 is a front elevation view thereof;

FIG. 3 is a right elevation view thereof;

FIG. 4 is left elevation view thereof;

FIG. 5 is rear elevation view thereof;

FIG. 6 is a top plan view thereof; and,

FIG. 7 is a bottom plan view thereof.

The broken lines in the drawings depicts portions of the remote control that form no part of the claimed design.
